SAFETY RAZOR

Jay T. Hellmann, Chicago, Ill.

Application November 24, 1943, Serial No. 511,588

10 Claims. (Cl. 30—60)

My invention relates to safety razors, and has among its objects and advantages the provision of an improved razor structure wherein the blade holder is mounted for pivotal movement and is opened with a snap action to separate the blade and its holder from the guard, thereby providing an arrangement which facilitates drying of the blade as well as maintaining the blade holder and the guard in separated relationship to facilitate placement and removal of the blade.

In the accompanying drawings:

Figure 1 is a front elevation of a safety razor embodying my invention, with a portion broken away for the purpose of illustration.

Figure 2 is a similar view with the razor rotated 90 degrees in one direction about the axis of its handle.

Figure 3 is a similar view but with the razor rotated 90 degrees in the opposite direction.

Figure 4 is a front elevation of the guard and stem structure.

Figure 5 is a view of the stem structure rotated 90 degrees in one direction.

Figure 6 is a view of the guard and stem structure rotated 90 degrees in the opposite direction.

Figure 7 is a plain view of the guard.

Figure 8 is a sectional view of the guard with a portion broken away at line 8—8 of Figure 7.

Figure 9 is a vertical section of the razor structure in the position of Figure 1.

Figure 10 is a similar view illustrating the blade and its holder in open position.

Figure 11 is a view similar to Figure 10 but illustrating the razor structure rotated 90 degrees.

Figure 12 is a sectional view along the line 12—12 of Figure 9.

Figure 13 is a cross section of the blade holder illustrating the blade latch.

Figure 14 is an inside view of the blade holder.

Figure 15 is an edge view of the blade holder partly in section.

Figure 16 is an end view of the blade holder.

Figure 17 is a side view of the connecting rod.

Figure 17a is a top view of the connecting rod.

Figure 18 is an end view of the connecting rod.

Figure 19 is a detailed view of an impeller member.

Figure 20 is a side view of the tubular sleeve.

Figure 21 is a view of the rod, as in Figure 19.

Figure 22 is an elevational view of the latch carrying member.

Figure 23 is a view of the latch carrying member rotated 90 degrees.

Figure 24 is an edge view of the latch.

Figure 25 is a sectional view along the line 25—25 of Figure 22.

Figure 26 is an elevation of the sleeve handle.

Figure 27 is a face view of a toggle latch.

Figure 28 is a view of the opposite side of the toggle latch.

In the embodiment of the invention selected for illustration, I make use of a guard 30 having the usual notched edges 32 and curved cross section.

One end of the guard 30 is provided with a square opening 183 having beveled edges flaring toward the convex side 189 of the guard. The other end of the guard is provided with a slot 54 which provides accommodation space for a pivoted finger 64. An inturned lip 50 is provided at this end of the guard. The inturned lip 50 has an opening 51 to slidably receive the flanged end of the connecting rod 108. Leading into the opening 51 is a slot 54 of the guard 30. The bevelled ledges 53 are located on the side of the slot 54 at the concave side of the guard, Figure 6. The notches 62 are located at either side of the inverted lip 50. A cut away section 52 and a groove 186 are provided in the upper part of the inturned lip 50. The groove 186 extends crosswise of the inturned lip and has its opening on the inside of the inverted lip. An open space 184 is provided to admit bar 60 of the blade holder 56.

Fixedly attached to the guard 30, Figure 4, is a tubular stem 34 having a bore 35, which bore extends longitudinally of the stem the entire length thereof. The diameter of the bore 35 is reduced at a point just short of the guard 30 which forms a shoulder 37 located inside the tubular stem which provides a stop means for the latch carrying member 80. The diameter of the bore 35 from the unattached end of the tubular stem to the shoulder 37 of proper dimension to slidably receive the latch carrying member 80. On one side of the tubular stem is provided a slot 36 extending the full length of the tubular stem and communicating with the bore 35. The width of the slot 36 is of proper dimension to slidably receive a lug 104 and a pressure block 110 formed on the member 84 and the flanged end 180—180 of the latch 78, Figure 10. On the opposite side of the tubular stem 34 is provided a slot 38 extending through its unattached end and part way the length of the tubular stem. The tubular member 34 is cut away to form openings 40 and 42 communicating with the slot 38, Figure 5, and these communicate with the bore 35. The slot 38 at its narrow end is of proper width to slidably receive link 144 and screw 148 of the toggle latch member 122 and the abutment block 150 of the tubular body 82 of the latch carrying member 80, Figure 22. Two lugs 44 are located on the edges of the tubular stem walls and are positioned between the cut away sections 40 and 42. The tubular stem 34 is provided with a short closed ended slot 124 cut through that

end thereof next to the guard 30. The open ends

of slot 124 of the tubular stem and the open end of slot 190 of the guard 30 communicate at the junction of the tubular stem 34 and the guard 30 forming an accommodation space for the latch 78 of the latch carrying member 80, when the latch 78 is moved in a clockwise direction. The closed end of the slot 124 is bevelled from within the bore 35 of the tubular stem 34 forming a camming edge 126, Figure 9. Two notches 48 are provided in the tubular stem and are located at the end of cut away section 42, Figures 4 and 5. Threads 49 are provided inside the unattached end of the tubular stem to receive a screw plug 182.

A blade holder 56, Figures 13, 14, 15 and 16, coacts with the guard 30 to clamp the razor blade 58 therebetween. This blade holder is provided with two lugs 59 at one end to support the bar 60. The bar 60 is provided with a finger 64 located in the midsection of the bar and extending diagonally therefrom. On the opposite side of bar 60 is provided a camming lug 194 which is in longitudinal alignment with the finger 64. The lugs 59 are properly spaced to receive therebetween the inverted lip 50. The blade holder 56 is placed in connected relationship with guard 30 by entrance of the bar 60 in the opening 184, Figure 7. When the blade holder 56 is in the clamped position shown in Figure 9 the bar 60 lies inside the inturned lip 50 in a suspended position and the camming lug 194 is free in the opening 52 of the inverted lip 50. When the blade holder 56 is pivoted from its clamped position as shown in Figure 9, to the open position of Figure 10, lug 194 cams against lower inside wall of the inverted lip 50, as at 57, Figure 8, forcing the bar 60 upwardly until bar 60 is nested in the groove 186 of the inverted lip as in Figure 10. Attached to the central part of the blade holder is a latch lug 72 which has a slot 74 terminating at a point near the unattached end of the lug 72 to provide a bar 76. The blade holder 56 is provided with a headed pin 68, Figure 13. The lugs 59 of the blade holder 56 are properly spaced to loosely accommodate therebetween the narrow end 66 of the razor blade 58. The head of pin 68 is of proper dimension to admit, under pressure, the slot 70 of the razor blade 58 and hold the razor blade in connected relationship with the blade holder 56. The razor blade 58 may be removed from the blade holder 56, Figure 11, by resting the thumb on the headed pin 68 and the index finger on the narrow end 66 of the blade 58 and applying light pull pressure against the end 66 of the razor blade. The space between the outer end of the inturned lip 50 and the concave side of the blade holder 56 is of proper distance to place the razor blade 58 under slight stress which enables utilization of the inherent spring action of the metal of the razor blade to effect pivotal operation of the blade holder 56 from the position of Figure 9 to the position of Fig. 10.

Means for retaining the blade holder 56 in the clamping position of Figure 9 are provided through the medium of a latch carrying member 80, Figures 22 and 23.

The latch carrying member 80 comprises a tubular body 82 having at one end lugs 84 between which a latch 78 is positioned and pivotally mounted by means of a pin 86. The latch 78 is provided at one end with a hook 79 to engage the bar 76 of the latch lug 72 and on the opposite side from the hook 79 is a lobe 81 which provides delaying means for the latch 78. The other end of

latch 78 is provided with two flanges 180 connected in their midsections by a bar 178 and a channel 176 is located between the flanges 180. The latch 78 has a round opening 85 in its center to receive the pin 86. The tubular body 82 has an eccentrically located and longitudinally extending bore 88, which bore terminates in the tubular body 82 at a point just short of the end wherein are located the lugs 84. The diameter of the bore 88 is of proper dimension to slidably receive therein the cylindrical body 96 and the tubular sleeve 100 of the member 94. One side of the tubular body 82 is provided with a flat faced surface 90 extending the greater length of the tubular body, and an abutment block 150 is located on the same side of the tubular body at the end of the flat faced surface 90, Figure 22. The opposite side of tubular body 82 is provided with a slot 92 extending the entire length of the tubular body and communicating with the bore 88 thereof. The width of slot 92 is of proper dimension to slidably receive therein the lug 104 and the pressure block 110 of the member 94, Figure 19, and the flanged end 180 of the latch 78 of the latch carrying member 80, Figure 24.

Means for operatively connecting the blade holder 56 with the latch carrying member 80 are provided which include the employment of a connecting rod 108, Figures 17 and 18. One end of the connecting rod 108 is provided with a hook 172, and other end of the rod is provided with two flanges 174, connected at their outer edges by a bar 116. The upper parts of flanges 174 have rounded edges 115 while the lower portions have notched edges as at 175. Between the flanges 174 is an opening 114 which is of proper dimensions to slidably receive endwise therein the finger 64 of the blade holder 56. The connecting rod 108 is arranged in connected relationship with the blade holder 56 and the latch carrying member 80 by placing bar 116 of the rod 108 slidably over the end of the finger 64 of the blade holder 56, and entering the hook end 172 in to the channel 176 to engage the bar 178 between the flanges 180 of the latch 78. Units of the razor thus connected are held in position through pressure from block 110 on the member 94.

The impeller member 94, Figures 19, 20 and 21 has a cylindrical body 96 having fixedly attached thereto and extending longitudinally therefrom a pressure block 110, which pressure block is of proper dimension to be slidably receivable in the slot 92 of the tubular body 82 and the slot 36 of the tubular stem 34. A tubular sleeve is provided with a concentrically located and longitudinally extending bore 105. The bore 105 is of proper diameter to slidably receive therein a rod 98. The tubular sleeve 100 is provided with a slot 106, cut into one side thereof and, extending a part way the length of the tubular sleeve to a point adjacent the closed end, and communicating with the bore 105. A rod 98 has a lug 104 fixedly attached to its side, which lug extends laterally therefrom. The other end of rod 98 is threaded into the cylindrical body 96. A compression spring 102 is mounted on the rod 98 abutting the cylindrical body 96 and the tubular sleeve 100. When parts of member 94 are assembled as a unit, Figure 19, the lug 104 is slidably accommodated in the slot 106 of the tubular sleeve, and abuts the closed end of the slot 106 of the tubular sleeve 100 to hold the parts in unit formation for convenient handling. When the razor is assembled as in Figures 9 and 10, the entrance of the lug 104 into slot 92 of the tubular body 82 and slot 36 of the tubular stem

34 provides means of locking the rod 93 in its screwed position in the cylindrical body 96.

A screw plug 182 has a center bore 183 which provides means of drainage. The screw plug 182 is threaded into the end of tubular stem 34 as at 49, Figure 5, and engages the end of tubular sleeve 180 of the member 94, which places the spring 102 under compression as in Figure 10, with additional compression when razor is in position of Figure 9.

The toggle latch, Figures 10, 27 and 28, comprises bars 128 and 130 pivotally connected by a pin 132. The bar 128 has two ledges 141 extending longitudinally therefrom to support the lip 136 of the cam 134. The cam 134 is pivotally mounted on the pin 132 for engagement with the flat faced surface 90 of the tubular body 82 to pivot the toggle latch 122 from its position of Figure 9 to that of Figure 10. The lip 136 is attached to the cam 134 and provides means for prying the cam 134 into camming engagement with the flat faced surface 90 of the tubular body 82. When the toggle latch is in position of Figure 10, the lip 136 contacts the ledges 141 of the bar 128 and gives the toggle latch the benefit of greater leverage pressure while forcing the toggle latch into its position as in Figure 9. The bar 128 is slotted at 138 for the reception of one end of the bar 130, and one end of the latter bar is slotted at 140 for reception of the cam 134. A pin 142 pivotally connects the bar 130 with the link 144. The link 144 has flanges 145, Figure 28, to slidably engage the edges 41 of the tubular stem 34. The link 144 slidably nests in slot 38 of the tubular stem 34 and is held in that position by means of sleeve handle 146 which slips over the stem 34. A screw 148, having a square head, is threaded into the free end of the link 144. The screw head of the screw 148 abuts block 150 of the tubular body 82 of the latch carrying member 80. The screw 148 provides adjustment means for gauging longitudinal movement of the latch carrying member 80 which governs the amount of clamp pressure applied to the blade holder 56. Since the screw 148 has a square head and is closely but slidably accommodated in the slot 38 of the tubular stem 34 there is provided a locking arrangement for the screw 148 to enable maintenance of any fixed adjusted screw position. A pin 152 pivotally connects the bar 128 with a head 154 and lies against the tubular stem 34. The head 154 has two flanges 156 shaped as continuations of the head 154. The lugs 158 are for engagement with the notches 48 of the tubular stem 34 to effectively hold the head 154 in the position of Figures 9 and 10.

The sleeve handle 146, Figure 26, slips partly over the flanges 156 to hold the head 154 to the edges 43 of the tubular stem 34, as at 42, Figure 5. The sleeve handle 146, in position of Figures 9 and 10, provides an outer closing housing for the slot 38 of the tubular stem 34 to provide space accommodation for the link 144 and the screw 148 of the toggle latch member 122 and also to provide similar space for the abutment block 150 of the tubular body 82 of the tubular latch member 80. A slot 160 in the sleeve handle 146 provides accommodation space for the toggle latch 122. The sleeve handle 146 has lipped edges 162 to engage edges 164 of the head 154 to hold the head 154 in its nested position in the opening 42 of the slot 38 of the tubular stem 34.

With the toggle latch 122 in position of Figure 9, the pin 132 lies to the right of a straight line passing through the pin 142 and 152; which arrangement holds the toggle latch 122 against

the flat faced surface 90 of the tubular body 82.

A cap nut 166 has an opening 167 and is threaded on the sleeve handle 146 to enclose the screw plug 182. The opening 167 is for drainage purposes. The screw plug 182 has engagement with the end of sleeve handle 146 to hold the sleeve handle in assembled relationship with the tubular stem 34. The cap nut 166 provides a locking arrangement for the screw plug 182 to prevent the latter from becoming disengaged from the tubular stem 34 when razor is in operative use.

The razor as in Figures 9 and 10 may be easily and quickly dismounted and all parts removed without use of tools by simply removing the cap nut 166 and the screw plug 182.

The razor blade 58 is attached to the blade holder 56 when razor is in the open position of Figure 10.

The blade holder 56 is pivoted from the open position of Figure 10 to the closed position of Figure 9 by manual energy, in the following manner: The thumb is rested on lip 136 of the cam 134 of the toggle latch 122, when in position of Figure 10, and pressure is applied thereto in the direction of the flat faced surface 90 of the tubular body 82 of the latch carrying member 80 which extends the toggle latch 122, directing pressure through screw 148 of the link 144 against abutment block 150 of the tubular body 82 to drive the latch carrying member 80 in a direction away from the guard 30. Member 94 is slidably housed within the bore 88 of the tubular body 82 of the member 80, and is carried with the latch carrying member 80 in its movement in the direction away from the guard 30. The member 94 is held in its connected relationship with the latch carrying member 80, and in the bore 88 of the tubular body 82 by pressure from the spring 102.

As soon as latch carrying member 80 commences movement in a direction away from the guard 30, the lip 136 of the toggle latch is forced in the direction of the flat faced surface 90 of the tubular body 82, and the back side of the hook 78 of the latch 79 contacts and cammingly engages the edge 126 of the slot 124 of the tubular stem 34, forcing the latch 78 in a counterclockwise direction, drawing the flanged end 139 of the latch 78 toward the tubular body 82 and directing pull pressure on the connecting rod 108 to draw the rod 108 in an endwise movement toward the tubular body 82. This pull pressure is transmitted to the blade holder 56 through contact of the bar 116 of the rod 108 against upper edge of the finger 64, of the bar 60, of the blade holder 56 thereby, pulling the finger 64 toward the tubular body 82 with sufficient force to pull the blade holder 56 from its open position of Figure 10 to its closed position of Figure 9. Upon the blade holder 56 reaching closed position of Figure 9, the latch 78 is drawn farther inside the tubular stem 34 causing the hook 78 to engage the bar 76 of the latch lug 72 to clamp the blade holder 56 in the position of Figure 9.

The blade holder 56 is disengaged from the clamped position of Figure 9 and pivoted to the open position of Figure 10 by means of compression spring energy, applied when the toggle latch 122 is released from its extended position as in Figure 9. When the toggle latch 122 is thus released the latch carrying member 80 is driven in the direction of the guard 30 by member 94 through pressure block 110 of the member 94. When latch carrying member 80 has moved a short distance in the direction of the guard 30, the hook end of the latch 78 is in slot 124 of the

tubular stem 34, permitting the latch 78 to commence a clockwise movement, which disengages the hook 79 of the latch 78 from the bar 76 of the latch lug 72. When the hook 79 disengages the bar 76 of the latch lug 72, the latch carrying member 80 comes to a stop and the shoulders 81 of the tubular body 82 of the latch carrying member 80 abut shoulder 37 in the bore 35 of the tubular stem 34. With the latch carrying member thus stopped in its movement in the direction of the guard 30, by continued clockwise movement of the latch 78, the member 84 continues to drive the pressure block 110 in the direction of the guard 30, the flanges 180 of the latch 78 are driven against the guard 30, and the connecting rod 108 through the engagement of the bar 178 of the latch lug 78 and the hook 172 of the rod 108, is driven to its full extended position as in Figure 10. In the endwise movement of the connecting rod 108 from its position in Figure 9 to that of Figure 10, the opening 114 of the rod 108 closes end-wisely over the finger 64 of the blade holder 56 and the notched edges 175 of the flanges 174 of the rod 108 cammingly enter the space over the bar 60 of the blade holder 56, forcing the flanged end of the bar 60 to an elevated position with relation to the bar 60, and diverting pressure to the lower edge of finger 64, thereby forcing the finger 64 upward with sufficient force to impel the blade holder 56 from closed position of Figure 9 to open position of Figure 10.

The blade holder 56 is held in the position of Figure 10 by the upper side of finger 64 which abuts the inside edge of the bar 116 of the connecting rod 108, while the other side of the finger 64 abuts end 177 of the rod 108, and the notches 175 of the flanges 174; thereby pressingly engaging the edge of the bar 60 of the blade holder 56.

Without further elaboration, the foregoing will so fully explain my invention, that others may, by applying current knowledge, readily adapt the same for use under various conditions of service.

I claim:

1. A safety razor guard having (1) a square opening at one end, said square opening having its edges bevelled, (2) a first slot extending longitudinally of the guard in a direction of, and intersecting the edge of, a round opening located in the center of the guard, (3) two notches with an inturned lip therebetween at the other end of the guard, (4) a groove within the inturned lip, said groove opening inwardly of the inturned lip and extending crosswise therein, (5) an oblong section removed from central upper side of the inturned lip, (6) a square opening in the lower central side of the inturned lip, (7) a second slot in the guard extending longitudinally of the guard in a direction of, and intersecting the edge of, the square opening in the lower side of the inverted lip, (8) two bevelled ledges in the concave side of the guard, extending longitudinally of the guard, and positioned one at either side of the second slot of the guard, (9) and an opening between the end of the inturned lip and the end of the guard, said opening extending crosswise of the guard.

2. A safety razor tubular stem having (1) a first slot through one end of the tubular stem wall, extending longitudinally of the tubular stem a short distance to a closed end, said closed end being bevelled from within the tubular stem, (2) a second slot on same side of tubular stem, through the other end thereof, extending longitudinally of the tubular stem, said second slot being enlarged at midsection of the tubular stem,

said enlarged section of the second slot having a closed end in the tubular stem wall, (3) two lugs in the edges of the tubular stem wall located in the enlarged section of the second slot, (4) two notches in the tubular stem wall located at the end of the enlarged section of the second slot of the tubular stem, (5) a third longitudinally extending slot located in opposite side of the tubular stem and extending the entire length of the tubular stem, (6) a shoulder inside the tubular stem, (7) and threads inside one end of the tubular stem.

3. A safety razor blade holder having (1) a headed pin attached to concave side of the blade holder and located at one end of the blade holder, (2) a latch lug having one end attached to central section, concave side, of the blade holder, said latch lug having a slot therethrough, and a cross bar located in the unattached end of the latch lug, (3) two lugs attached to blade holder, located at other end of blade holder, for support of a bar which is suspended between these two lugs, said bar having fixedly attached to one of its sides, centrally located of the bar, a finger extending diagonally of the bar, and said bar having fixedly attached to its opposite side, centrally located of the bar, a camming lug, said camming lug extending diagonally of the bar and arranged to be in parallel alignment with the finger.

4. A safety razor latch carrying member comprising (1) a tubular body having a concentrically located and longitudinally extending bore extending the greater length of the tubular body, (2) a flat faced surface and an abutment block on one side of the tubular body, (3) a slot on other side of the tubular body extending longitudinally therewith and entire length of the tubular body, said slot intersecting the bore of the tubular body, (4) two lugs at end of tubular body extending longitudinally therefrom, said lugs being for support of a latch which is pivotally mounted between the said two lugs through means of a pin, said latch having at one end a hook, on the back side of which is a lobe, in the center a round hole, and at the other end two round flanges connected at their mid-sections by a bar.

5. A safety razor connecting rod having (1) a hook at one end, (2) two flanges at other end, said flanges having round upper edges and connected in their upper end sections by a bar, (3) an opening in the flanged end of the connecting rod lying between the flanges and between the bar that connects the said flanges and the end of the connecting rod between the said flanges.

6. A safety razor impeller member comprising (1) a cylindrical body having fixedly attached thereto and longitudinally extending therefrom, a pressure block, a cylindrical body having at other end a center bore which is threaded, (2) a rod having a lug fixedly attached to one side of the rod, said lug located near one end of the rod and extending therefrom, and other end of rod threaded into the bore of the cylindrical body, (3) and a tubular sleeve having a center bore extending the entire length of the tubular sleeve, said tubular sleeve having a slot, intersecting the bore, and extending a part way the length of the tubular sleeve.

7. A safety razor toggle latch member comprising, (1) a head having two circumferentially arranged and longitudinally extending lugs at one end of the head, two shoulders at either side of

head, two longitudinally extending flanges at other end of head, and a slot in the head between the flanges, said slot being crosswisely intersected by a pin through the head, (2) a first bar having a round hole in one end to receive said pin and two flanges at other end of the first bar, said flanges having round holes in their center sections to receive a pin, said flanges of the first bar having longitudinally extending ledges, (3) a second bar having a hole in one end to receive a second pin and two flanges at other end of the second bar, these flanges having round holes in their mid sections to receive a third pin, (4) a camming latch having an ovalled shaped disk with a round hole flatwise through upper side of said disk to receive said second pin, said disk having at its upper edge and fixedly attached to the disk, a lip extending longitudinally therefrom, said lip having drop ledges at either side thereof, (5) a sliding link having at one end two flanges with a slot therebetween, said slot being crosswisely intersected by a round hole to receive said third pin, and opposite end of sliding link has an adjustment screw threaded thereinto.

8. A safety razor holder, comprising a guard, a blade holder mounted for pivotal movement with respect to the guard to engage or release a blade thereon, a tubular member engaging the guard, a latch carrying member in the tubular member, said blade holder having a keeper extending through the blade and guard and engaged by the latch in the latch carrying member, means for moving the blade holder to an open position when the latch is released, and a toggle means for releasing the latch carrying member.

9. A safety razor holder, comprising a slotted guard, a blade holder mounted for pivotal movement with respect to the guard to engage or release a blade thereon, a tubular member engaging the guard, a latch carrying member in the tubular member, said blade holder having a keeper extending through the blade and guard and engaged by the latch on the latch carrying member, spring means for moving the blade holder to an open position when the latch is released, toggle means for releasing the latch carrying member, and said latch carrying member having a tubular part, and a spring pressed member in said tubular part having a block actuating the latch carrying member.

10. A safety razor holder, comprising a slotted guard, a blade holder mounted for pivotal movement with respect to the guard to engage or release a blade thereon, a tubular member engaging the guard, a latch carrying member in the tubular member, said blade holder having a link connection at its pivoted end with the latch carrying member and provided with a keeper extending through the blade and guard to be engaged by the latch on the latch carrying member, spring means for moving the blade holder to an open position when the latch is released, toggle means for releasing the latch carrying means, said latch carrying member having a tubular part, and a spring pressed means in the tubular part of the latch carrying member for actuating the latch carrying member.

JAY T. HELLMANN.
